UNITED STATES PATENT OFFICE

MORRIS F. FINKELSTEIN, OF NEW YORK, N. Y.

ELECTRIC FITTING FOR CIRCUIT-WIRING.

1,103,748.

Specification of Letters Patent. Patented July 14, 1914.

Application filed November 17, 1911. Serial No. 660,868.

To all whom it may concern:

Be it known that I, MORRIS F. FINKELSTEIN, a citizen of the United States, and a resident of the city of New York, (borough 5 of the Bronx,) in the county and State of New York, have invented a new and Improved Electric Fitting for Circuit-Wiring, of which the following is a full, clear, and exact description.

10 This invention relates to electric fittings and has reference more particularly to a fitting including or constituting a connection for electric conductors, comprising an insulating casing, clamping plates within 15 said casing and spaced apart to receive the end of a wire therebetween, and means for moving one of the plates toward the other to engage and clamp the wire.

An object of the invention is to provide 20 a simple, strong and durable electric fitting which can be fashioned from different materials adapted for the purpose, which is susceptible of a variety of uses, by means of which electric conductors can be readily and 25 securely connected, by means of which the electrical connection effected is an excellent one, and which can be easily manipulated.

A further object of the invention is to 30 provide an electrical connection which can be used for various purposes in electric light, signal and other installation, in which the insulating casing comprises a single piece, in which the conductors are securely held against accidental displacement notwithstanding 35 that they can be readily attached and released, which requires but a single screw or other like member to hold it in position, which may have any suitable ornamental form to correspond with the 40 rounding ornamentation, by means of which soldered splices can be eliminated, and whereby the necessity of using a gasolene torch or like device is obviated when connecting wires.

45 A still further object of the invention is to provide a conductor connection which is so strongly constructed that the insulating and concealed parts cannot be readily injured, by means of which short circuits can be obviated, as well as the possibility of contact

55 with current-carrying parts, in which the contacting parts are thoroughly embedded in insulating material and are thus not liable to come in contact with adjacent objects, and in which the conductors are securely gripped between contacting surfaces of material dimensions, whereby a thorough securing of the conductor and an excellent electric contact are assured.

60 The invention consists in the construction and combination of parts to be more fully described hereinafter and particularly set forth in the claims.

65 Reference is to be had to the accompanying drawings forming a part of this specification, in which similar characters of reference indicate corresponding parts in all the views, and in which—

70 Figure 1 is a longitudinal section of a wire connector constituting an embodiment of my invention; Fig. 2 is a transverse section on the line 2—2 of Fig. 1; Fig. 3 is a plan view of the wire connector.

75 Before proceeding to a more detailed explanation of my invention, it should be clearly understood that the insulating casing of each instrument may be fashioned from porcelain, composition, or any other suitable material adapted for the purpose. For the contact-making parts I prefer to 80 employ brass or similar metal possessing a high degree of conductivity.

85 Referring to the drawing, the figures illustrate a wire connector by means of which two or more wires can be gripped and joined. The connector comprises two preferably cylindrical members 110 having therein longitudinal bores 111 each provided with a reduced part 112 terminating at an enlarged end opening 113. Within the reduced bores 111 is a metallic sleeve 114 in which are received U-shaped clamping members 115, the inner adjacent faces of which are preferably roughened. These clamping members receive the bared ends of the conductors 116 which are introduced through the openings 112 and 113. The sleeve 114 has threaded openings 117 in which are received the clamping screws 118 located in openings 119 of the members 110. A guard 90

95

100

is rotatably mounted upon the connector by means of a split spring ring 120. It has a longitudinally extended, rounded cap or cover 121 which normally serves to cover up the openings 119. At the ends, the spring ring has inwardly disposed parts 122 forming projections adapted to engage in recesses 123 of the connector members. In this way the ring serves to lock the guard 16 in an operative and an inoperative position and prevents its accidental displacement. In Fig. 1 is shown a single conductor introduced into the connector at one end, while in Fig. 3 I have illustrated a plurality of 15 conductors joined with a single connector.

While the drawing illustrates a pair of C-shaped clamping members 115, disposed with the clamping ends toward the end of the tubular member 114, a single member 20 provided with clamping ends can be substituted for the two shown in the drawing and it will answer the same purpose.

It will be noted that the openings 119 are so proportioned that they receive loosely the 25 clamping screws 118. Consequently, when the device is first assembled these screws can be readily inserted in the openings and will then be held in place against accidental removal by the cover 121. This obviates the 30 necessity for screwing the screws partly into the threaded openings 117, and thereby time, labor and expense are saved. When the device is to be used, and after the ends of the wires have been inserted in the U-shaped 35 clamping members, the elements 118 can then be screwed into the openings 117 to tighten the clamps. The clamps, it will be noted, in effect constitute oppositely disposed spring-controlled jaws within which 40 the ends of the wires are received.

Having thus described my invention, I claim as new and desire to secure by Letters Patent:

1. A connector for electric conductors, 45 comprising an insulating casing, a clamp within said casing adapted to engage and grip a wire, a clamp-operating member, said casing having an opening adapted to receive said operating member loosely, and means 50 for retaining the operating member loosely in the opening.

2. A connector for electric conductors, 55 comprising an insulating casing, a clamp within said casing adapted to engage and grip a wire, a clamp-operating member, said casing having an opening adapted to receive and hold said member loosely when the said member is inoperative with respect to said clamp, and a movable cover adapted to close 60 said opening.

3. A connector for electric conductors, 65 comprising an insulating casing, a pair of oppositely disposed clamps within said casing, said casing having openings for permit-

ting the introduction of the ends of conductors into said clamps, clamp-operating members, said casing having further openings adapted to receive and hold said members loosely when the same are inoperative with respect to said clamps, and a cover for 70 said last-mentioned openings, said cover having limited movement relative to said casing to permit said last-mentioned openings to be covered and uncovered.

4. A connector for electric conductors, 75 comprising an insulating casing, a conducting sleeve therein having a threaded opening, said casing having an opening registering with said threaded opening and of greater dimension than the same, a clamping 80 screw adapted to be received in said threaded opening and to be received loosely in said other opening, a clamping member in said sleeve adapted to be controlled by said screw and means on said casing for retaining said 85 screw in the opening of the casing.

5. A connector for electric conductors, 90 comprising an insulating casing, a conducting sleeve therein having a threaded opening, said casing having an opening registering with said threaded opening and of greater dimension than the same, a clamping screw adapted to be received in said threaded opening and to be received loosely in said other opening, a clamping member in said 95 sleeve adapted to be controlled by said screw, and a cover upon said casing and movable relative thereto and adapted to extend over said opening of said casing.

6. A connector for electric conductors, 100 comprising an insulating casing, a clamp therein having jaws tending normally to open, said casing having means whereby said clamp is held against bodily movement, a member in said casing for operating said 105 clamp to close the same, and means making said last-mentioned member normally inaccessible.

7. A connector for electric conductors, 110 comprising an insulating casing, a conducting sleeve therein, a pair of oppositely disposed clamps located in said sleeve and each comprising jaws tending normally to open, means for holding said clamps against 115 bodily movement, said sleeve and said casing having registering openings adapted to receive clamping screws, clamping screws located in said openings and each controlling one of said clamps and a cover for said openings of the casing, rendering normally said 120 screws inaccessible.

8. A connector for electric conductors, 125 comprising an insulating casing, a conducting sleeve therein, a pair of oppositely disposed clamps located in said sleeve and each comprising jaws tending normally to open, means for holding said clamps against bodily movement, said sleeve and said casing

having registering openings adapted to receive clamping screws, clamping screws located in said openings and each controlling one of said clamps, and a movable cover on 5 said casing adapted to extend over said openings.

In testimony whereof I have signed my

name to this specification in the presence of two subscribing witnesses.

MORRIS F. FINKELSTEIN.
